UNITED STATES PATENT OFFICE.

JULIEN PERSOONS AND ALPHONSE PERSOONS, OF CHILDONCK, NEAR LOUVAIN,
BELGIUM.

YIELDING BEARING.

1,107,998.

Specification of Letters Patent.

Patented Aug. 18, 1914.

Original application filed February 21, 1912, Serial No. 679,127. Divided and this application filed March 10, 1913. Serial No. 753,149.

To all whom it may concern:

Be it known that we, JULIEN PERSOONS and ALPHONSE PERSOONS, subjects of the King of Belgium, residing at Childonck, near Louvain, in the Kingdom of Belgium, have invented certain new and useful Improvements in Yielding Bearings, of which the following is a specification.

This invention relates to a guiding device 10 or yielding bearing for the shaft or spindle carrying the drum in centrifugal cream separators of that class in which is made use of a freely suspended drum such as described in our former Patent No. 946985 and 15 in our pending application for a patent Serial No. 679127 filed Feb. 21, 1912, of which this application is a division.

One object of our invention is to provide an improved guiding device in which the 20 resistance to the movements of the shaft or spindle from the center is increased automatically with the extent of the movements or oscillations of the shaft or spindle, said action being absolutely progressive while at 25 the same time extremely reliable.

A further object of our invention is to simplify the construction of such guiding devices.

With these objects in view, our invention 30 essentially consists in the special arrangement and combination of parts as herein-after fully described and pointed out in the appended claims.

Referring to the annexed drawing: Figure 1 is a vertical section of a centrifugal cream separator provided with a guiding device constructed according to our invention. Fig. 2 is a horizontal section through the guiding device at an enlarged scale. 40 Fig. 3 is a vertical section of the guiding device shown in Fig. 2.

The drum 1 of the cream separator is suspended as usual from the shaft or spindle 2 adapted to be rotated by a gearing 3. The 45 construction of said gearing is well known and corresponds substantially to that shown and described in our former Patent No. 946985. The shaft or rod 2 from which the drum is suspended requires as usual to be 50 guided below the ball bearing 9 for the hollow shaft 10 in which the said shaft or rod 2 passes downwardly.

The guiding device is of the kind in which pins or pistons are pressed against 55 the circumference of the shaft or rod 2 and

consists of four pins 5 pressing with their ends 6 against the rod or spindle 2 and lodged in grooves of a cup member 7, the upper part of which forms a cup 8 supporting the cup containing the balls 9. The 60 pins 5 terminate near the outer periphery of the cup member 7 in conical surfaces 11 which are surrounded by four metal wires 12 wrapped about the cup member 7 (Fig. 2) and having their ends fixed to said cup 65 member. The device thus formed is attached by a bolt (not shown) in the space 13 in the frame 14 of the separator. It will be readily understood that owing to this arrangement the guiding device has a pro- 70 gressively increasing action. The oscillations of the shaft or rod 2 are transmitted to the pins 5 which tend to be displaced horizontally in the grooves of the cup mem- 75 ber 7 in which they are lodged. Owing to the conical form of the external surface 11 of the pins 5, these latter begin to act on the lowest wire 12 and, according as the amplitude of the swings of the shaft or rod 2 increases, the surfaces 11 successively act on 80 two, three or four wires so that the resistance to the swings of the shaft or rod 2 ap- 85 preciably increases with the amplitude of the said swings.

In the lower part of the space 13 is 85 screwed a metal plug piece 15 for insuring tightness at this part of the frame. The space 13 communicates through a hole 16 with the box 17 of the frame 18 containing the gear 3 so as to return thereto the lubri- 90 cant which collects in the space 13 owing to the movement of the mechanism.

The described arrangement could evi- 95 dently be reversed, that is to say the end surfaces 11 of the pins 5 could be in a ver- 100 tical plane on the condition that the wires 12 be wrapped conically about the cup-mem- 105 ber 7 or that the plane containing the wires be disposed at an angle with the plane of the end surface 11 of the pins 5. The four wires 12 shown in Fig. 3 could also be re- 110 placed by a single wire suitably wrapped or coiled about the cup member 7 and the pins 5 could be provided with semi-circular end- surfaces without modifying the action of the device.

What we claim is:

1. The combination with the shaft of a centrifugal cream separator of pins ar- 110 ranged radially around said shaft, a cup-

member in which said pins are guided horizontally and wires wrapped about said cup-member, the plane containing said wires forming an angle with the end-surfaces of 5 said pins coöperating with said wires.

2. The combination with the shaft of a centrifugal cream separator of pins arranged radially around said shaft, a cup-member in which said pins are guided horizontally, wires wrapped about said cup-member and pressing the pins against the 10 shaft, and end-surfaces formed on the pins

and coöperating with said wires whereby the number of wires pressing the pins against the shaft is increased with the extent of the movement of the pins in the cup member. 15

In testimony whereof we have affixed our signatures in presence of two witnesses.

JULIEN PERSOOONS.

ALPHONSE PERSOOONS.
